UNITED STATES PATENT OFFICE

WILLIAM B. COFFMAN, OF NORWOOD, OHIO

COAL CONVEYING AND DISCHARGING DEVICE

Application filed March 11, 1926. Serial No. 93,929.

My invention relates to means for conveying and discharging coal or coke into stoker hoppers and the like.

The objects of my invention are to provide coal-loading and conveying mechanism which will be simple, efficient, economical and easily operated for the purpose of supplying the coal or coke to stoker hoppers and the like.

10 My invention consists in providing a track leading to furnace hoppers on which coal-buckets are drawn upwardly by a suitable chain hoist and emptied by means attached to said track.

15 My invention also consists in the construction, combination, location and arrangement of parts, as herein set forth and claimed.

In the drawings:

Fig. 1 is a view partly in elevation, partly 20 in section and partly in dotted lines to show the construction and operation of the invention;

Fig. 2 is a vertical cross-section taken on the line 2—2 of Fig. 3;

25 Fig. 3 is a perspective view of one of the coal-buckets;

Fig. 4 is a front elevation of Fig. 1;

Fig. 5 is a vertical cross section taken on a line 5—5 of Fig. 1;

30 Fig. 6 is an enlarged perspective view of one of the tracks showing one of the hook stops attached thereto;

Fig. 7 is a side elevation thereof showing the hook stop in dotted lines; and

35 Fig. 8 is a perspective view of the lower end of one of the tracks showing a modification.

In the embodiment of my invention as illustrated and which shows a preferred construction I provide usual furnace 1, boilers

2, automatic stoker 3 and stoker hopper 4.

Heretofore it has been the custom to manually fill hopper 4 with coal 5 by shoveling the coal from coal pile 6. After the hopper

45 4 is filled with coal 5, stoker-piston 7, operated by suitable mechanism 8, forces the coal into furnace 1 through opening 9. Thus far

I have described the present method of feeding coal into a furnace after the hopper 490 has been filled.

Furnaces equipped with automatic stokers require hopper 4 to be continuously filled with fuel, such as coal or coke. To do this mechanically and to eliminate the necessity of manually shoveling fuel into said hopper 4 I provide a plurality of coal buckets 10 all of which are of exactly the same construction. Said buckets 10 comprise bottom 11, incline front 12, back 13 and sides 14 and 15, respectively. Rollers 16 are 55 mounted on the bottom 11 of said bucket 10 to facilitate the movement of the bucket from the coal pile 6 to the furnace 1. U-shaped handle 17 has its ends terminating in eyes 18 and 19, respectively, which 60 are pivotally received over studs 20 and 21, said studs being integral with reenforcing strips 22 and 23 which are secured to the coal-bucket 10 by bolts 24. Rollers 25 and 26 are located near the inclined front 12 and 65 towards the top of bucket 10 and are rotatably mounted on roller studs 27 and 28. Said studs 27 and 28, respectively, have shoulders 27' and 28' and reduced threaded ends 27'' and 28'' which are inserted through 70 holes 29 and 30 in bucket 10 and which receive nuts 31 and 32. Tracks 33 and 34 L-shaped or angular in cross section, are secured to floor 35 by brackets 36 and bolts 37 and are inclined towards hopper 4, as 75 shown in Fig. 1. The upper ends of L-shaped tracks 33 and 34 are bent downwardly, as shown in Figs. 6 and 7, forming holding members 38 and 39 which hook over edge 4' of hopper 4 and are rigidly secured 80 thereto by bolts and nuts 40. Hook stops 41 and 42 are secured to the upper ends of L-shaped tracks 33 and 34 by bolts and nuts 43. Said stops are provided with brace strips 44 and 45 to retain the shape of the 85 hooked ends, as shown in Fig. 6.

In the modified construction of track, an integrally formed foot 36' is bent at an angle thereto to form floor attaching means.

The operation of my device is as follows: 95

The coal bucket 10 is filled with coal 5 from coal pile 6 and then rolled over to L-shaped tracks 33 and 34. The bucket 10 is turned so that inclined front 12 fits between the guides of said tracks, and rollers 100

25 and 26 ride on the edge of said guides, as shown in Figs. 1 and 4. Then suitable lifting mechanism, such as chain hoist 46 is hooked under U-shaped handle 17, as shown in Fig. 1. When said hoist is operated bucket 10 is drawn upwardly until rollers 25 and 26 engage hook stops 41 and 42. As the rollers 25 and 26 engage hook stops 41 and 42 the bucket 10, being pivotally attached to U-shaped handle 17 is dumped, as shown by dotted lines in Fig. 1. Then the hoist is lowered, thereby lowering bucket 10 which may be unhooked from said hoist and rolled over to coal pile 6 and refilled 15 with coal 5 whereby the operation of dumping the coal into hopper 4 is repeated.

10 An advantage of my invention is that one man can keep a number of hoppers filled with less hard work than was heretofore required by several men to produce the same amount of work.

20 Another advantage of my invention is that the labor cost for loading stoker hoppers is reduced to a minimum.

25 Heretofore the coal pile has usually been located a considerable distance from the stoker, requiring that it be shoveled therefrom to the floor immediately in front of the stoker and then shoveled up into the 30 hopper. This is not only a slow and laborious means but it also involves keeping a pile of coal in front of the stoker where it is in the way of workmen.

35 An advantage of my invention is that the coal can be drawn any desired distance from the coal pile to the stoker in the buckets and drawn up the track and dumped, thus keeping a neat and clean floor and avoiding any obstruction to the workmen. 40 Furthermore, in many boiler rooms there is very little space in front of the stoker where coal could be piled.

45 Another advantage of this invention is that without any inconvenience the coal, as it is being used, can be weighed and a record thereof kept for the comparative value of the coal being used, as well as for other purposes.

50 Having thus described my invention, what I claim as new and desire to secure by Letters Patent is:

1. In a coal conveying and discharging device, an inclined track comprising a pair of spaced apart angle bars forming supports and guides, a fixed stationary hook stop mounted on the upper end of each angle bar outside of its track laterally thereof and extending upwardly and rearwardly, a detachably mounted bucket adapted to be drawn upwardly upon said track between said guides and laterally engaging means on said bucket adapted to engage said stops to dump said bucket.

65 2. In a coal conveying and discharging device, an inclined track comprising spaced

apart angle bars each having an integral downwardly turned attaching strip at its upper end and provided with a hole therethrough, a bolt and nut whereby said attaching strip is adapted to be secured at its upper end, means at its lower end adapted to bear against the floor and means for attaching it thereto.

3. An inclined track, stops supported by and adapted to project from the sides of said track, a coal bucket, rollers on the sides of said bucket near its upper edge adapted to engage said stops and pivot thereon, and means for drawing said bucket upwardly on said track whereby said stops and rollers will dump said bucket.

4. A coal conveying and discharging device comprising inclined spaced apart tracks each having a hook stop at the upper end thereof and placed outside laterally of said tracks, respectively, a bucket having a bail pivoted thereto centrally thereof near its bottom, said bucket having an outwardly and upwardly inclined side and provided with roller bearing studs adjacent said inclined side near the top whereby when said bucket is drawn upwardly on said track said roller bearing studs will enter said hook stops and form a pivot bearing whereby, as said bucket is continued to be drawn upwardly it will tilt forwardly and discharge the contents thereof, substantially as set forth.
